ABSTRACT OF THE DISCLOSURE

Ferroelectric and piezoelectric compositions consisting essentially of a solid solution of the ternary system

wherein from 0 to 25 atomic percent of the Pb^{+2} is replaced by an alkaline earth metal is disclosed. The constituents are defined by the formula

$$X+Y+Z=100$$

wherein X, Y and Z are in the following ranges, taken with reference to the figure ABCDEFGH in FIG. 1:

	X	Y	Z
A	75	0	25
B	60	10	30
C	10	60	30
D	5	55	40
E	5	45	50
F	15	30	55
G	35	10	55
H	55	0	45

Also disclosed is a binary system consisting of from 55 to 75 mole percent $\text{Pb}(\text{InNb})_{0.5}\text{O}_3$ and from 45 to 25 mole percent PbTiO_3 wherein from 0 to 25 atomic percent of the Pb^{+2} is replaced by an alkaline earth metal.

CROSS-REFERENCE TO RELATED APPLICATION

This application is a continuation-in-part of Ser. No. 712,192, filed Mar. 11, 1968, entitled "Ferroelectric and Piezoelectric Composition," by the same inventors as the present application, and now U.S. Pat. No. 3,630,908.

BACKGROUND OF THE INVENTION

Field of the invention

This invention relates to a novel ferroelectric and piezoelectric composition.

Description of the prior art

Ferroelectric and piezoelectric materials containing barium titanate, lead titanate zirconate and the like as their principal constituents are used in many diverse applications, such as transducers useful in devices such as wave filters for producing or sensing vibrations, elements for generating high voltage and the like.

2

SUMMARY OF THE INVENTION

The present invention provides a ferroelectric and piezoelectric material having a novel composition consisting essentially of a solid solution of a ternary system consisting of $\text{Pb}(\text{InNb})_{0.5}\text{O}_3$, PbTiO_3 and PbZrO_3 , in the amounts shown above, wherein from 0 to 25 atomic percent of the Pb^{+2} is replaced by an alkaline earth metal.

The present invention also contemplates a ferroelectric and piezoelectric composition consisting essentially of a solid solution of a binary system consisting of from about 55 to about 75 mole percent $\text{Pb}(\text{InNb})_{0.5}\text{O}_3$ and from about 45 to about 25 mole percent PbTiO_3 , wherein from 0 to 25 atomic percent of the Pb^{+2} is replaced by an alkaline earth metal.

15 A ferroelectric and piezoelectric material prepared in accordance with the present invention is characterized by intense ferroelectric and piezoelectric properties which are obtained by applying a DC voltage to a sintered ceramic material in the same manner by which ceramics of barium titanate or lead titanate zirconate are made, thereby polarizing the ceramic and providing a residual polarization to the ceramic. This property enables the ceramic to be advantageously used in transducers in all types of electrical devices.

BRIEF DESCRIPTION OF THE DRAWINGS

FIG. 1 is a triangular compositional diagram illustrating the various embodiments of the present invention.

30 FIG. 2 is a diagram illustrating curves which indicate variations in the longitudinal coupling coefficient and the dielectric constant, respectively, of the material produced in accordance with the present invention when the ratio of lead titanate with respect to lead indate niobate is varied.

35 FIG. 3 is a diagram illustrating the curves which indicate the variation in the longitudinal coupling coefficient and the dielectric constant, respectively, of the material produced in accordance with the present invention when the ratio of lead titanate with respect to lead zirconate is varied and the content of lead indate niobate in the material is held to 10 mole percent.

DETAILED DESCRIPTION OF THE PREFERRED EMBODIMENTS

40 45 The material produced in accordance with the present invention is composed of

50 with from 0 to 25 atomic percent of the Pb^{+2} being replaced with an alkaline earth metal.

All of the ceramics made of the ternary system in accordance with the present invention possess piezoelectric properties. However, from the viewpoint of industrial interest, the subject matter of the present invention is directed to the following range of each constituent of the material referred to in the diagram in FIG. 1:

Mole percent

X ----- 5-75
Y ----- 25-55
Z ----- 0-60

65 wherein $X+Y+Z=100$.

The values of the coupling coefficient k_{33} and the dielectric constant ϵ of the material are maximums at positions adjacent to the phase boundaries of

PbTiO_3 and PbZrO_3 in the ternary system shown in FIG. 1, i.e., the above values are maximum when the content mole percent of each constituent is to fall on the lines connecting each of the middle points of sample numbers 19-23, 18-22, 16-21, 15-20, and 4-5 in FIG. 1. The above values decrease as the composition of the material is varied from the above described regions. From an industrial viewpoint, the preferred boundary is selected in the present invention to conform to the numerals A-B-C and E-F-G-H in FIG. 1.

The composition of the material containing

is superior from the viewpoint of ease of sintering and polarization of the material in comparison with the binary system consisting of PbTiO_3 - PbZrO_3 . Further, the Curie point of the composition containing $\text{Pb}(\text{InNb})_{0.5}\text{O}_3$ is higher than that of the composition which does not contain $\text{Pb}(\text{InNb})_{0.5}\text{O}_3$. The Curie point of composition sample number 16 is about 50° C. higher than that of a binary system in which the ratio of Zr to Ti is kept at about the same ratio as that of sample number 16. Accordingly, the lower limit of the composition wherein the inclusion of $\text{Pb}(\text{InNb})_{0.5}\text{O}_3$ is recognized to give advantageous results is represented by the numerals C-D-E-F in FIG. 1.

In preparing the ceramic in accordance with the present invention, oxides such as In_2O_3 , Nb_2O_5 , TiO_2 , ZrO_2 and the carbonates of the peroxides thereof which can easily be decomposed by heating to form the oxides may be utilized as raw materials. Since ZrO_2 usually contains a small amount of hafnium, it is possible to replace Zr by hafnium in the present invention. However, since hafnium is expensive in comparison with Zr, the selection of the constituents should be made from an industrial viewpoint.

EXAMPLE

The oxides in Table 1 were used as raw materials in powdered form since these were commercially available at a purity greater than 99.5%. The oxides were mixed together after each of the oxides was weighed to obtain the weight ratio shown in Table 1. The mixture was then dried, and heated at 800° C. for two hours so as to effect a temporary sintering thereof.

The temporarily sintered material was coarsely crushed, finely powdered and wet blended in a ball mill for 20 hours.

After the powdering and blending, an organic caking agent was added to the powder, and the thus prepared mixture was pressed so as to form a cylindrical shape having a diameter of 6 mm. and a length of 18 mm. The thus formed body was sintered in a platinum casing at a temperature ranging from 1230 to 1270° C. for three hours within an atmosphere of lead. The sintered body was ground into a shape having a diameter of 5 mm. and a length of 15 mm. with the opposite ends of the body being glazed with silver paint.

The thus-formed element was polarized by applying a DC voltage of 2.5 kv./mm. in silicone oil at a temperature of 100° C. After the expiration of 100 hours from the time of polarization of the element, the physical properties of the element were measured by the methods defined by the IRE standard. Table 1 shows the test results, the longitudinal coupling coefficient being indicated by k_{33} , and the dielectric constant being indicated by ϵ . The variation in properties due to the change in the ratio of $\text{Pb}(\text{InNb})_{0.5}\text{O}_3$ with respect to PbTiO_3 is shown in FIG. 2. The variation in the properties due to the change in the ratio of PbZrO_3 with respect to PbTiO_3 when the con-

tent of $\text{Pb}(\text{InNb})_{0.5}\text{O}_3$ is kept at 10 mole percent is shown in FIG. 3.

TABLE 1

Composition—Properties (refer to Fig. 1)

5	Composition, mole percent			Sintering temp., ° C.	k_{33} , percent	ϵ
	$\text{Pb}(\text{InNb})_{0.5}\text{O}_3$	PbTiO_3	PbZrO_3			
10	80	20	0	1,230	22	500
2	75	25	0	1,230	40	810
3	70	30	0	1,230	52	1,100
4	65	35	0	1,250	57	1,300
5	60	40	0	1,250	50	1,020
6	55	45	0	1,250	40	800
7	60	50	0	1,250	27	680
8	45	55	0	1,250	12	580
15	60	30	10	1,250	42	870
9	50	30	20	1,250	41	500
10	40	30	30	1,250	42	550

12	20	30	50	1,250	46	530
13	10	30	60	1,270	45	500
14	50	40	10	1,250	53	760
20	30	40	30	1,250	61	1,100
17	20	40	40	1,250	56	630
18	10	40	50	1,250	60	320
19	5	40	55	1,270	45	550
20	50	45	5	1,250	45	750
21	30	45	45	1,250	62	1,150
22	10	45	45	1,250	64	1,220
23	5	45	50	1,270	52	920
25	30	50	20	1,250	42	610
25	10	50	40	1,250	38	570
26	5	50	45	1,250	62	630
27	35	55	10	1,250	39	600
28	15	55	30	1,270	41	740
29	40	20	40	1,250	37	470
30	50	20	30	1,250	35	460
31	30	60	10	1,250	25	420
32	10	60	80	1,250	27	300
33	0	55	45	1,270	45	770

Sample numbers 2-6 and 9-28 are included within the claims, whereas sample numbers 1, 7, 8 and 29-33 are excluded from the claims for the previously mentioned reasons though they also illustrate the piezoelectric properties.

It is well known in the art that mechanical losses in a ceramic composed of the ternary system

can be reduced, and the dielectric constant thereof increased, by replacing a portion of the Pb^{+2} with an alkaline earth metal. A similar effect can be obtained in the ternary system

produced in accordance with the present invention by replacing a part of the Pb^{+2} with an alkaline earth metal.

Accordingly, from 0 to 25 atomic percent of the Pb^{+2} in the composition of the present invention is replaced with an alkaline earth metal. Any of the alkaline earth metals can be employed, with strontium, barium, calcium and mixtures thereof being preferred.

The following Table 2 shows the increased dielectric constant of the composition of the present invention when a portion of the Pb^{+2} is partially replaced with an alkaline earth metal. In Table 2, k_{33} represents the longitudinal coupling coefficient and ϵ represents the dielectric constant.

TABLE 2

65	Composition			Pb^{+2} substituted amount x (atomic ratio)	k_{33} , percent	ϵ
	Pb (InNb) _{0.5} O ₃	PbZrO_3	PbTiO_3			
70	10	45	45	0	64	1,220
	10	45	45	$\text{Ba}^{+2}0.025$	65	1,300
	10	45	45	0.05	67	1,800
	10	45	45	0.10	67	2,200
	10	45	45	0.15	65	2,700
	10	45	45	0.20	65	3,100
	10	45	45	$\text{Sr}^{+2}0.05$	65	1,800
	10	45	45	$\text{Ca}^{+2}0.025$	64	1,500
75	30	27.5	42.5	0	60	1,200
	30	27.5	42.5	$\text{Ba}^{+2}0.05$	58	2,400

What is claimed is:

1. A ferroelectric and piezoelectric composition consisting essentially of a solid solution of a binary system consisting of from about 55 to about 75 mole percent $Pb(InNb)_{0.5}O_3$, and from about 45 to about 25 mole percent $PbTiO_3$, wherein a portion of up to 25 atomic percent of the Pb^{+2} in said composition is replaced by an alkaline earth metal, said portion being an amount sufficient to increase the dielectric constant of said composition.

2. The composition of claim 1 wherein said alkaline earth metal is strontium, barium, calcium or mixtures thereof.

3. A ferroelectric and piezoelectric composition consisting essentially of a solid solution of a ternary system consisting of about 10 mole percent $Pb(InNb)_{0.5}O_3$, from about 45 to about 50 mole percent $PbZrO_3$ and from about 40 to about 45 mole percent $PbTiO_3$, with the total mole percent being 100 percent, and wherein a portion of up to 25 atomic percent of the Pb^{+2} is replaced by an alkaline earth metal, said portion being an amount sufficient to increase the dielectric constant of said composition.

4. The composition of claim 3 wherein said alkaline earth metal is strontium, barium, calcium or mixtures thereof.

5. A ferroelectric and piezoelectric composition consisting essentially of a solid solution of a ternary system consisting of about 30 mole percent $Pb(InNb)_{0.5}O_3$, from about 25 to about 30 mole percent $PbZrO_3$ and from

about 40 to about 45 mole percent $PbTiO_3$, with the total mole percent being 100 percent, and wherein a portion of up to 25 atomic percent of the Pb^{+2} is replaced by an alkaline earth metal, said portion being an amount sufficient to increase the dielectric constant of said composition.

6. The composition of claim 5 wherein said alkaline earth metal is strontium, barium, calcium or mixtures thereof.

7. A ferroelectric and piezoelectric composition consisting essentially of a solid solution of a ternary system consisting of about 50 mole percent $Pb(InNb)_{0.5}O_3$, from about 5 to about 10 mole percent $PbZrO_3$ and from about 40 to about 45 mole percent $PbTiO_3$, with the total mole percent being 100 percent, and wherein a portion of up to 25 atomic percent of the Pb^{+2} is replaced by an alkaline earth metal, said portion being an amount sufficient to increase the dielectric constant of said composition.

8. The composition of claim 7 wherein said alkaline earth metal is strontium, barium, calcium or mixtures thereof.
